SHORT WAVE RECEIVER

Harold M. Lewis, Douglaston, N. Y., assignor to
Hazeltine Corporation, a corporation of Delaware

Original application September 25, 1931, Serial
No. 565,024. Divided and this application April
27, 1934, Serial No. 722,614. In Germany Sep-
tember 21, 1932

10 Claims. (Cl. 250—20)

The present invention relates to a tuning system, or, more particularly, to such a system for use in a short wave receiving apparatus. Exemplary of such a system is that used in a short wave converter.

This application is a division of my copending application Serial No. 565,024, filed September 25, 1931, now Patent No. 2,001,277, dated May 14, 1935.

10 A short wave converter is an apparatus which, when used in conjunction with any broadcast receiver, permits the reception of short wave signals by the said broadcast receiver. The converter comprises an oscillator and modulator, by 15 which the short wave signal currents are converted into currents of a frequency within the tuning range of the broadcast receiver. The current of this frequency, which frequency will be referred to hereinafter as the "intermediate frequency", is amplified, detected and reproduced 20 by the broadcast receiver.

The frequency range covered by the short wave band is approximately from 1500 kc. (200 meters) to 20,000 kc. (15 meters). This range of 25 frequencies is so great that it is not practical to tune a circuit through the entire range by the variation of a single tuning element. Some arrangement must be provided for changing both 30 of the frequency determining elements; that is, both the inductance and the capacity. In accordance with the usual practice the tuning is actually done by varying the capacity of a variable condenser, and the inductance is changed in steps to permit the condenser to tune the circuit 35 throughout the various portions of the range.

It is common practice to divide the short wave band into several bands which will be referred to in this application as the "short wave band," the "middle wave band", and the "long wave 40 band".

The inductances used in tuning the radio-frequency circuits of the short wave receiver, or the radio-frequency circuit and oscillator circuits of a converter, are usually wound on removable 45 forms commonly known as "plug-in" coils, which coils are changed when desiring to go from one of the short wave bands to another. A system of this type has the disadvantages that it is expensive to manufacture and requires shifting of 50 coils when operating.

Various systems have been proposed by which the inductance of the tuning coils is changed in steps by means of switches. However, the leads and switch mechanisms introduce capacities 55 which considerably lessen the range of the tuning

condensers, and usually the resulting large number of points to be switched has condemned this system.

Furthermore, considerable difficulty is experienced in constructing an oscillator capable of 5 covering such a broad range of frequencies, as there is a considerable difference in the feedback coupling needed at the two ends of the short wave band.

It is the object of the present invention to overcome the above noted difficulties and provide a system in which the inductance values of a single winding may be varied in steps by providing a system in which the leads required for changing the inductances are relatively short and have 15 negligible capacity effects. It is a further object of this invention to provide an oscillator coupling system having a simple structure, not involving the use of moving parts, by which the coupling effect may be simultaneously altered 20 as the frequency determining inductance is changed, to permit the oscillator to oscillate effectively throughout the entire short wave band.

These and further objects of this invention will become apparent from the following specification taken in connection with the appended 25 claims and drawings.

In accomplishing the objects of the present invention the inductance of the frequency determining circuit of the converter oscillator is provided with a switch for short-circuiting the long wave portions thereof and long wave and middle wave portions thereof, when operating the oscillator to receive signals in the middle wave band 30 and short wave band, respectively. Dual magnetic and capacitative feedback couplings are provided between the plate circuit of the oscillator and the grid coil when operating within the middle wave band. When operating in the long wave band the inductive coupling is negligible, and the feedback is essentially through the capacitative coupling between the plate and grid 35 circuits. When operating in the short wave band the capacitative coupling effect becomes negligible, whereas the coupling between the circuits 40 due to the inductive coupling, is considerable.

Provision is also made for obtaining a uniform coupling between the antenna circuit and the input of the modulator. A straight inductive coupling is utilized when receiving signals within 50 the short wave and middle wave band. When operating in the long wave band an auto-transformer effect is obtained by connecting the antenna circuit to include a portion of the long wave section of the grid inductance. 55

The modulator and oscillator windings are so arranged relative to the switches for short-circuiting their unused portions and relative to the grids of the modulator and oscillator tubes that the leads, particularly when the converter is operating in the short wave band, are as short as possible.

In order to permit the continuous rotation of the tuning dial in either direction to progressively tune the converter through the entire band, the condensers used in both the modulator input and oscillator circuits are each provided with double stators and double rotors so constructed that when the capacity between one of the pair of rotors and stators is maximum, that between the other pair of rotors and stators is minimum.

Switching means are provided, operated simultaneously with the switches for short-circuiting the unused portions of the tuning inductances, for connecting the appropriate sections of the condensers.

Series condensers are provided for connection in the oscillation circuit for each of the bands and are appropriately connected in circuit by a switch operated together with the previously mentioned switches, when the range of the converter is shifted from one band to the other. The padding condensers for the section of the oscillator tuning condenser, which is used for the middle wave band, is provided in shunt with this section. A condenser is connected from the middle wave band tap of the inductance to the stator of the condenser, so that when the entire tuning inductance is in use this condenser may act as a padding condenser for the long wave band. This condenser is then essentially in shunt with the section of the variable condenser in use. When the long wave section of the inductance is short-circuited, however, as when operating in the middle wave band, this condenser is in parallel with the series condenser in use at that time.

The condenser shaft has an indicator dial geared thereto so arranged that it rotates a complete revolution for each half revolution of the condenser shaft. This dial has thereon three indicating scales, the outer scale being for indicating the frequencies in the short wave band, and the inner scale being for indicating the frequencies in the long wave band. The scales pass by indicator lights placed behind the dial within a compartment which permits illumination of but a single scale by each lamp, and a switch operated simultaneously with the wave changing switches operates to light the appropriate scale. A full description of this feature of the present invention is given in an application of Harold Miller Lewis for "Tuning scale", Serial No. 565,027, filed September 25, 1931, now Patent No. 1,987,857, dated January 15, 1935.

In order to permit the operation of a single control knob to control the frequency of reception, regardless of which of the three bands the converter is operating in, there is provided a gang switch mechanism operated by the condenser control knob at the appropriate instant as the dial is rotated from one to the other of the frequency bands. This feature of the present invention is fully described in an application of Harold Miller Lewis for "Switching arrangement", Serial No. 565,026, filed September 25, 1931.

It can thus be seen that an arrangement has been provided by which the set can be tuned through the entire short wave band by the operation of a single control, and by which the frequency for which this apparatus is set to respond

is automatically indicated at all times as the set is tuned.

In order to prevent the reception of broadcast signals by the receiver used in conjunction with the converter, the leads between the converter, as well as the converter itself, are completely shielded. The antenna input of the converter contains a trap circuit to prevent currents of undesired frequency being impressed upon the input of the modulator and amplified thereby. The plate supply of the modulator contains a tuned radio-frequency choke which is tuned roughly to the intermediate frequency and thereby tends to by-pass currents of frequencies differing greatly therefrom which have been received in the converter. The full details of this portion of the present invention are given in an application of Harold Miller Lewis for "Short wave receiver arrangement", Serial No. 565,025, filed September 25, 1931, now Patent No. 2,000,084 dated May 7, 1935.

Attention is now invited to the accompanying drawings in which:

Fig. 1 is a circuit diagram of the converter embodying the present invention;

Fig. 2 is a simplified circuit diagram of the converter circuit as connected when the switch is in the long wave position;

Figs. 3 and 4 are elementary diagrams for use in explaining the operation of the oscillator circuit;

Fig. 5 is a simplified diagram of the modulator circuit;

Fig. 6 is a diagram of an alternative modulator circuit;

Figs. 7 and 8 represent the secondary and primary windings respectively of the antenna coupling transformer used in the converter comprising the present invention; and

Figs. 9 and 10 represent the secondary and primary respectively of the oscillator coil.

Referring now to Fig. 1, the antenna circuit includes the antenna 10, the ground 11, the trap circuit 12, comprising the inductance 13 and condenser 14, the primary winding 15, and a portion 45 of the secondary winding 16. The inductance 13 and the condenser 14 of the trap circuit 12 are so proportioned that said circuit is resonant to the intermediate frequency produced by the short wave converter. The input circuit of the converter is connected to the grid of modulator device 17, which may be any thermionic tube, though that shown is of the screen-grid type. The input circuit is tuned by means of the condenser 21, which may be a double condenser employing, as shown, a single rotor and two stators so arranged that the capacity obtained between the rotor and one stator is maximum, when the capacity between the rotor and the other stator is minimum. The connections to the stators are controlled by means of the switch 23. The actual condenser includes two stators and two rotors, so arranged that when one rotor is entirely within its stator, the other rotor is entirely out of its stator. The function of the condenser and switch arrangement will be explained later.

The tapped secondary 16 is connected by means of switch 24, so that any of the tapped portions of the secondary may be included in the input circuit. The switch is so connected that the unused portions of the winding are short-circuited.

For producing the heterodyne frequency for combining with the incoming signal and thus producing the intermediate frequency, there is provided the oscillator 25. This oscillator tube is 75

of the single grid type and includes in its grid circuit the secondary 40 of the oscillation transformer, the primary 42 of which is connected in the plate circuit which includes stopping condenser 43. The secondary 40 is a tapped winding similar to 16 of the antenna transformer, and the connections to said secondary are controlled by means of switch 34. The grid return of the oscillation circuit is completed through the biasing resistor 27, which is connected to the cathode of the tube 25. The frequency of the oscillation circuit is determined by means of condenser 31, which is similar to condenser 21, and is connected to be operated therewith in a unit control manner by means of the control knob 22 associated with the indicator dial 26.

The connections to the two continuously variable portions of the condenser 31 are controlled by means of switch 33.

Padding condensers 41M and 41S are provided across the two portions of condenser, as shown, for the purpose of aligning the oscillation circuit with the input of modulator 17 in the middle wave range and short wave range, respectively. Padding condenser 41L is connected across the long wave portion of the inductance winding 40, so that when the switch 34 is on contact L this condenser is practically in shunt with the condensers 31 and 41S for adjusting the alignment in the long wave range. When the switch 34 is on contact M, the condenser 41L is in shunt with condensers 31 and 37, and the total series capacity is at that time the sum of these three condensers.

In series with condenser 31 is provided a series capacity which is variable in steps, comprising condensers 36, 37 and 38, the connections to which are controlled by means of the switch 35. Each of these condensers is provided with the padding condenser 36', 37', or 38', respectively, for the purpose of correcting the alignment of oscillator circuit with the modulator input in the various frequency bands. In the middle frequency band, as has just been stated, the condenser 41L is in shunt with 37 and 37'. Coupling coils 44 and 45 coupled to the middle and long wave portions of the secondary 40, respectively, are included in the cathode circuit of the modulator 17. This circuit also includes the biasing resistor 46 shunted by by-pass condenser 47 for the purpose of causing tube 17 to act as a modulator.

The plate and screen-grid potential are provided by means of the power supply source 20 which, as shown, is of the ordinary double wave rectifier and filter type. This power supply also provides heater lighting current for heating the cathodes of tubes 17 and 25. A resistor 29 is included in the plate lead of the oscillator 25 for the purpose of reducing the plate potential thereof.

As shown, the dial 26 includes three scales, 26—a, 26—b, and 26—c, these scales covering the short wave band, middle wave band, and long wave band, respectively.

It is to be noted that in order to get better spacing of the frequency indicators, the short wave scale is placed in the outer position on the dial 26, as the condenser motion to get the frequency separation required to separate the various stations is less in the short wave band than it is in the long wave band.

For the purpose of indicating in which of the frequency ranges the converter is operating, each 75 of the scales is provided with one of the illumina-

tating lights 71—a, 71—b, or 71—c, controlled by means of switch 39 to light them when tuning through the short wave band, middle wave band, and long wave band, respectively.

Switches 23, 24, 33, 34, 35 and 39 are so arranged as to be simultaneously operated and also to be actuated by the control knob 22 as the condensers are tuned through the limiting capacities for one of the frequency bands. Thus, the rotation of the control knob 22 results in the actuation of the switches 23 and 33, resulting in switching of the connections to condensers 21 and 31, respectively, to give the opposite capacity extreme for the modulator and oscillator circuits. Switch 39 is simultaneously operated changing the lighting of the indicating lights and thus indicating the change in the frequency band by changing the indication from one to another of the scales. The specific means for actuating the switches constitute no part of the present invention, but are described fully in application of Harold Miller Lewis, for "Switching arrangement," Serial No. 565,026, filed September 25, 1931.

Included in the plate supply to the modulator 17 is the inductance 50. This inductance may have a high inherent capacity as indicated by capacity 51, or an actual condenser may be placed in shunt therewith. The inductance and capacity, however, are so proportioned that frequencies other than the desired intermediate frequency will be by-passed.

A connection from the output of modulator 17 is made through condenser 52 and lead 53 to the antenna binding post of the receiver 57. This connection is made through a shielded cable 54, which may, for example, be a BX cable, from the walls of which the lead 53 is spaced by means of bakelite spacers 56. Also connected through the cable 54 is the ground connection 55, which is connected to the ground binding post of receiver 57. The capacity 52 and the inherent capacity between the leads 53 and 55 are so proportioned that they constitute a dummy antenna to properly load the modulator 17, and to prevent misalignment of the input of receiver 57. Switch 59 is provided between the antenna 10 and the lead 53 by means of which the antenna may be directly connected to the input of the receiver 57 when it is desired to receive signals in the broadcast band directly on receiver 57.

The receiver 57 may be of any well known type, and is provided with the usual sound reproducing device 58. The specific details of neither 57 nor 58 constitute any part of the present invention.

The receiver is tuned to the intermediate frequency which it is desired to utilize, preferably 1,000 kc. The direct reception of signals of 1,000 kc., when the set is being operated to receive short wave signals by means of the converter, is prevented by means of the shielded cable 54. The modulator is prevented from acting as an amplifier of signals of 1,000 kc. frequency by means of trap circuit 12. Any signals of a frequency other than 1,000 kc. in the output of modulator 17 would be by-passed through the inductance 50. It is thus seen that a number of provisions have been made to prevent the interference of broadcast signals with the short wave signals being received by means of the converter.

In Fig. 2, to which attention is now invited, the circuit shown in Fig. 1 is again represented, except that the switches have been eliminated the connections being made as if the converter were tuned to some frequency within the long wave

band. In this circuit the high potential is represented as being supplied by means of the direct-current source 80, and the screen-grid potential of the device 17 is obtained therefrom by including a resistor 81 in the screen-grid circuit. The output of the oscillator circuit herein represented as 83 is fed to the cathode lead of the modulator 17 which, as has been described, is biased for grid bias detection. The incoming signal is fed through the oscillatory circuit 84 to the input of tube 17, which by means of the biasing resistor 46 operates as a rectifier or modulator, and thereby produces in its output circuit a distorted wave form from which a current of the intermediate frequency can be selected and supplied through the condenser 52 to the terminals A and G of the radio broadcast receiver.

It is to be noted that frequencies other than the intermediate frequency for which the radio broadcast receiver is to be adjusted are by-passed through the inductance 50, whereas this inductance and its inherent capacity form a high impedance path relative to currents of the intermediate frequency.

As previously stated, the circuit 12 acts to prevent currents of the intermediate frequency being received over the antenna 10 and amplified by the modulator 17, and the shielding of the lead 53 prevents a direct pick-up between the output of the device 17 and the input of the radio broadcast receiver.

The oscillator circuit 83 contains, as can be seen, the usual series condenser 38 in series with the tuning condenser 31, by means of which the circuit 83 is made to respond to a frequency continuously differing from the frequency to which circuit 84 responds by the amount of the intermediate frequency as the circuits are tuned in a uni-control manner.

Figs. 3 and 4 illustrate the means by which the single oscillation transformer is made to cover the considerable frequency range required of this type of equipment. The various portions of the inductance 40 are tuned by the respective parts 45 of the condenser 31 and thus constitute a tuned grid circuit.

In order to provide the offset frequency and thus permit alignment between the condensers 31 and 21 to permit ganging, a series condenser 36, 37 or 38 is provided. This condenser has the dual function of assisting the alignment and of permitting capacitative feedback action. The introduction of this capacity in the grid return requires a resistor 27 to prevent the grid from floating and to act as a grid bias resistor.

More specifically, Fig. 3 shows the action on the circuit when it is operating in the short wave and middle wave band. The used portion of the inductance 40 in these bands is relatively small and there is considerable coupling effect between the feedback inductance 42 and inductance 40. This is particularly true in the short wave band.

In the short wave band the capacitative feedback coupling is negligible. In the middle wave band, however, the capacitative feedback action is considerable. The inductive feedback action between 42 and 40 is less within this range, and the two couplings are so arranged as to give practically uniform operation throughout the middle frequency band.

Referring particularly to Fig. 4, in which the circuit represents the action of the oscillator circuit when operated in the long wave band, the inductive coupling between the coils 42 and 40 is

negligible, and the oscillator is of the capacity coupled type utilizing the series capacity 38.

Fig. 4 also represents the padding capacity arrangement. As can be seen from Fig. 1, the same section of the condenser 31 is utilized throughout the long and short wave bands. This complicates the arrangement required for the padding capacity of these two bands. The usual padding condenser 41M, however, is provided for the middle frequency band. The usual padding condenser 41S is also shunted across the section of the condenser used for the long and short wave bands. This capacity is adjusted for the short wave bands, and it has been found that it should have a very low value. For padding the condenser 31 for operation in the long wave band, the condenser 41L is shunted across that portion of the coil which is in use only during operation in the long wave band. The few turns of winding 40, not shunted by this condenser, are negligible when operating within the long wave band, so that the condenser 41L is essentially in parallel with the condenser 31. However, as can be seen from Fig. 1, when the switch 34 is on contact M for operation in the middle frequency band, the condenser 41L is in parallel with the condensers 37 and 37', the capacities of which are, therefore, adjusted to form the total series capacity which is required for producing alignment within the intermediate frequency band.

It can thus be seen that a substantially uniform feedback coupling is obtained throughout all three of the wave bands.

An important feature of the present invention is that as there is but a single tuning stage in the input to the modulator device, the oscillator frequency is the principal determinate of the frequency to which the converter is set to respond. This, it can be seen, increases the tuning range of the converter somewhat beyond what would be the case if the condenser 21 determined the range. As an example, when using a 1,000 kc. intermediate frequency and tuning the oscillator between 3,000 and 9,000 kc., which is a 3:1 ratio, the incoming frequency which can be received will vary between 2,000 and 8,000 kc., giving a receiving frequency ratio of 4:1.

Fig. 5 shows the modulator of Figs. 1 and 2 arranged for comparison with the circuit shown in Fig. 6.

Fig. 6 shows an alternative form of modulator circuit in which the grid-leak type of detection is used. This type of circuit gives slightly better sensitivity than that shown in Fig. 5, which latter is the usual grid bias arrangement and gives a better noise level but less sensitivity.

In Fig. 6 the low resistance grid biasing resistor 46 and its shunt condenser 47 have been removed, and the grid leak 46' and grid-leak condenser 47' in the grid circuit of the tube 17 have been substituted therefor.

Although it is clear that the specific coils for use in a converter constructed in accordance with the present invention will depend upon the characteristics of various other elements and upon the frequency ranges to be considered, the inductances used in covering the frequency ranges from 1,740 kc. to 19,400 kc. are shown in Figs. 7-10, and will now be described.

Fig. 7 illustrates the antenna coupling secondary. This secondary is wound on a $1\frac{1}{8}$ inch form 60 and comprises $69\frac{3}{4}$ turns of No. 18 B & S gauge enameled wire wound 20 turns per inch. The terminal 61 is connected to the grid of the tube 17 and the terminal 62 is connected to the 75

ground 11. The tap 64 is taken to include 5½ turns and is connected to contact S of switch 24. The tap 65 is taken to include 20½ turns and is connected to contact M of switch 24. The terminal 63 is connected to the antenna coil 15 and is taken 5½ turns from terminal 62.

The primary of the antenna coupling transformer is wound on ¾ inch form 67 and is placed inside the form 60 of Fig. 7, and spaced therefrom by means of spacer 68. The winding 15 comprises 18 turns of No. 26 B & S gauge enameled wire wound 24 turns per inch. The terminals 69 and 70 are connected to the trap circuit 12 and terminal 63 of winding 16, respectively.

15 The oscillator secondary winding 40, shown in Fig. 9, comprises 43¾ turns of No. 18 B & S gauge enameled wire wound on 1¼ inch form 72, 20 turns per inch. The terminal 73 is connected to contact L of switch 34 and the contact 74 is connected to the grid of oscillator tube 25. The tap 75 is taken 5½ turns from the end of coil and the terminal 75 is connected to contact S of switch 34. The terminal 76 is tapped 15¼ turns from the end of the coil and is connected to contact M of switch 34.

The feedback coupling coil 42 and the modulator coupling coils 44 and 45, shown in Fig. 10, are all wound on a ¾ inch form 77 which is placed inside of form 72 and spaced therefrom by means of spacer 78. The winding 42 comprises 4½ turns of 30 B & S gauge enameled wire close wound. Terminals 81 and 82 of winding 42 are connected to the contact L of switch 34 and the oscillator plate condenser 43, respectively. Windings 44 and 45 comprise 5 and 4½ turns, respectively, of No. 30 B & S gauge enameled wire close wound. Winding 45 is spaced ¼ inch from winding 42, and windings 44 and 45 are spaced approximately 2½ inches apart. These coils are connected in series and are connected by terminals 85 and 86 to the cathode of modulator 17 and the modulator bias resistor 46, respectively.

The condensers used have a maximum capacity of 195 microfarads and a minimum capacity of 19 microfarads.

Using the coils just described, the calibrated range of the converter is:

	Kilocycles	Meters
Long wave band.....	1740-4180	(163-72)
Middle wave band.....	3800-9075	(79-33.1)
Short wave band.....	8650-18,400	(34.8-15.5)

55 Certain other constants which have been found satisfactory are included:

Resistance 27=250,000 Ohms
 Resistance 29=25,000 Ohms
 Resistance 46=3,000 Ohms
 Condenser 36=450 Micromicrofarads
 Condenser 37=1,500 Micromicrofarads
 Condenser 38=1,500 Micromicrofarads
 Condenser 43=.1 Microfarad
 Condenser 47=.1 Microfarad

60 Although any appropriate tubes may be used a UY224 has been found appropriate for use as modulator 17 and UY227 has been found to be appropriate for use as the oscillator 25. The power supply device may be provided with the usual UX280, although it is to be understood that any appropriate power supply arrangement may be substituted for that shown.

I claim:

75 1. A superheterodyne receiving system for re-

ceiving signals covering a plurality of wave length bands, comprising a modulator input circuit, and an oscillation circuit tunable by ganged condensers, said input circuit including an inductance and one of said condensers, said oscillation circuit including an inductance, a series condenser, and another of said ganged condensers, and a feedback circuit comprising an inductance magnetically coupled to said oscillation circuit, and also including said series condenser and means for simultaneously varying the inductance of said modulator input and oscillation circuits, and the series condenser of said oscillation circuit for determining the wave length band to be received.

2. A superheterodyne receiving system for receiving signals covering a plurality of wave length bands, comprising a plurality of ganged condensers, modulator input and oscillator circuits tunable by said ganged condensers; said input circuit including one of said ganged condensers, an inductance, means for short-circuiting portions of said inductance to permit wide variations in the response of said circuit, an antenna transformer coil coupled to a portion of said inductance and connected through a second portion of said inductance to ground, whereby the coupling of said input circuit is varied as portions of the inductance are short-circuited; and said oscillator circuit including an oscillation circuit having an inductance, a series condenser, and another of said ganged condensers, and a feedback circuit comprising an inductance magnetically coupled to said oscillation circuit, and also comprising said series condenser and means for simultaneously varying the inductance of said modulator input and oscillation circuits, and the series condenser of said oscillation circuit for determining the wave length band to be received.

3. In a superheterodyne receiver adapted to receive signals covering a broad band of frequencies by continuous tuning through a plurality of steps in said band, a tunable input circuit for said receiver, an oscillation generator of the thermionic vacuum tube type, including a grid circuit, a frequency-determining network in said circuit, comprising a variable inductance, a condenser variable in steps, and a continuously variable condenser tuning said circuit, and a feedback circuit including an inductance magnetically coupled to the first-mentioned inductance and including said condenser variable in steps, said condenser variable in steps being adjusted for each step to set the frequency of the oscillation generator uniformly higher in frequency than the input tuning frequency of said receiver.

4. In a heterodyne radio frequency apparatus designed to permit continuous tuning through a plurality of contiguous wave bands which comprises a modulator and a tunable input circuit therefor, and an oscillator, including grid and plate circuits, said grid and plate circuits each including an inductance, the inductance of said circuits being inductively related, said grid circuit including means for short-circuiting portions of said inductance, two inversely varying condensers selectively connected in shunt with said inductance, a series alignment condenser for each of said bands selectively connected in series with said inversely varying condensers for assisting the coupling of said grid and plate circuits as well as the alignment of the modulator and oscillator circuits, a padding condenser in shunt with each of said inversely varying con-

densers, and a capacity so connected that it is alternatively in parallel with the series alignment condenser coupling said grid and plate circuits, and connected as a padding condenser in 5 shunt with the inversely varying condenser then in the circuit, when tuning in a selected wave band and the contiguous longer wave band, respectively.

5. In a heterodyne receiving arrangement a 10 receiver input circuit, an oscillator circuit in which the coupling between the grid and plate circuits thereof is maintained substantially constant throughout a broad band, said oscillator circuit including grid and plate circuits, an inductance in said grid circuit, means for short-circuit a portion of the inductance of the grid circuit to vary the effective inductance thereof to make large changes in the frequency of said oscillator, a connection common to said grid and 15 plate circuits, whereby the coupling between said circuits is simultaneously varied as the portion of the grid inductance is short-circuited, said grid and plate circuits each including a common condenser, which condenser has the dual function 20 of causing the alignment of the receiver input and oscillator circuits to permit uni-control tuning of said circuits, and assisting in the coupling of the two circuits.

6. In a heterodyne receiving system, an oscillator circuit adjustable to produce oscillations 30 covering a broad wave length band, subdivided into a short wave band, a middle wave band and a long wave band, said oscillator comprising an oscillator tube, grid and plate circuits for said tube, said grid circuit comprising a tuning inductance, a switch connected so as to short-circuit a portion of said inductance to cause said oscillator to respond to frequencies throughout 35 a plurality of wave length bands, a condenser shunted across said inductance, a series alignment condenser for each of the wave length bands, switching means for connecting the appropriate alignment condenser in the circuit, and said plate circuit including a stopping condenser, 40 an inductance, and the series alignment condenser, said last-mentioned inductance being inductively related to the short wave band portion of said tuning inductance and connected to the low potential end thereof, and a modulator circuit 45 for said receiving system including a modulator tube, an input circuit for said tube, including a tuning inductance, a variable condenser for tuning said inductance, an antenna circuit inductively related to said tuning inductance and connected thereto, switching means for short-circuiting 50 portions of said tuning inductance to alter the wave band through which the modulator is adapted to operate, a cathode circuit inductively related to the oscillator tuning inductance, and means 55 for simultaneously operating all of said switching means.

7. In a superheterodyne receiving system, a 60 converter for producing a predetermined difference frequency between any received frequency and a locally generated frequency in any of a plu-

rality of bands of frequency, including a first tuned circuit for selecting the received frequency and a second tuned circuit for determining the locally generated frequency, said first circuit comprising inductance variable in steps and a 5 continuously variable condenser; said second tuned circuit comprising inductance variable in steps, a condenser variable in steps and a continuously variable condenser; switching means for simultaneously varying said inductances and 10 said condenser variable in steps for operation in any one of said bands and uni-control means for simultaneously tuning with said continuously variable condensers to receive a desired frequency and produce said difference frequency. 15

8. In a heterodyne receiving system for reception in a plurality of bands of frequency, a frequency selecting circuit for tuning in said plurality of bands comprising inductance variable in steps and a continuously variable condenser, an 20 oscillating circuit to provide in each of said bands a local frequency differing from said selecting circuit frequency by a predetermined frequency, said oscillating circuit including a frequency-determining circuit comprising inductance variable 25 in steps, a condenser variable in steps and a continuously variable condenser, and switching means for simultaneously changing both of said inductances variable in steps and said condenser variable in steps. 30

9. In a heterodyne receiving system in accordance with claim 8, a vacuum tube generator for generating the local frequency and including said oscillating circuit to determine the locally generated frequency and having plate and grid circuits, 35 said condenser variable in steps being included in both plate and grid circuits to provide a feedback path between said plate and grid circuits, the values of capacity of said last-mentioned condenser being such that the mutual capacitive reactance of said path becomes larger when the frequency band in use becomes lower. 40

10. In a heterodyne receiving system, an oscillation generator of the thermionic vacuum tube type and a frequency-selecting circuit, said oscillation generator including grid and plate circuits, a frequency-determining network to tune one of said circuits, said network including a variable inductance, a first condenser adjustable in steps, and a second condenser which is variable; feedback means between said grid and plate circuits including inductive reactance; uni-control means for simultaneously modifying said variable inductance and the value of capacity of said first condenser whereby the effective coupling between the grid and plate circuits is maintained substantially uniform throughout a broad wave band; and said frequency-selecting circuit including means for tuning it to respond to a frequency having a constant difference relationship to the frequency-determining circuit of said oscillation generator, said last mentioned means including said condenser which is adjustable in steps. 55 60
